By Luther Johns, Atty.

UNITED STATES PATENT OFFICE

HOWARD B. JONES, OF EVANSTON, ILLINOIS

MULTIPLE-CONNECTION DEVICE

Application filed February 21, 1925. Serial No. 10,739.

These improvements relate to devices for making a plurality of electrical connections at one and the same time. In the form illustrated the device is a socket member adapted to cooperate with a multiple connection plug member, and full details of the plug member and certain details of the socket member will be found illustrated, described and claimed in my copending application, Serial No. 10 622,241, filed March 2nd, 1923.

The improvements have been designed particularly with a view to providing means for simultaneously making and breaking a considerable number of circuits which will be 15 found in a radio receiving set. In my said copending application I have shown a socket member secured upon a panel board or the like. I have found it desirable to provide such a connection member for application 20 within the cabinet of such a receiving set whereby the lead wires may extend to and from the socket member more advantageously, as where the cable leading to these connections may be brought to the rear or a side 25 wall of the set in an out-of-the-way position and the wires leading to the terminals of the set may be disposed more free of other wires or parts, whereby the pulling and pushing strains of breaking and making the connections will be communicated to a more 30 stable part, whereby the panel board will be free of this element, and the more difficult operation of boring through the panel board with a substantially large boring instrument 35 is avoided, and all to the effect of making an unusually strong connection member which may be applied for use within a cabinet, either to the base board as shown or to side or end walls of the cabinet in the most 40 advantageous position.

Figure 1 of the drawings shows a fragment of a cabinet wall with the present improvements in operative relation thereto; Fig. 2 shows the device in a side view with a multiple connection plug element fragmentarily shown by dotted lines; Fig. 3 is a rear view of the device, and Fig. 4 is a medial vertical section of the socket device parts shown in Fig. 2.

50 I provide a supporting member having a

normally upstanding arm 10 and a base part 11 adapted to be secured as by screws to the base board or some other part of the cabinet. This supporting member is preferably of metal, as cast brass, in order that it may be 55 quite strong and able to withstand considerable pulling and pushing strains imparted to the plug element 12, shown by dotted line and fully described in my said copending application.

Secured to the supporting member is a mounting 13 of insulating material, preferably in the form of a disc or circular plate which interfits telescopically with the casing part of the plug member. The means for holding the mounting 13 is shown as a tubular member 14 having its inner end flared outwardly at 15' for holding effect, this barrel 14 extending through the disc 13 and through the supporting member, there being a sleeve-like nut 15 at its inner end for binding the disc 14 and supporting member firmly together. This bolt 14 is made tubular so that it may accommodate a centrally-arranged guiding stem 17 on the plug member shown sectionally in Fig. 3, which stem 17 has a groove cut longitudinally therein to accommodate the pin 18, whereby the plug member 12 may be united with the socket member in only one given relation.

Passing through the disc 13 are a plurality of relatively long and narrow contact members 20 and 20^a spaced apart from each other, extending substantially parallel with each other and beyond the inner face of the disc 13 and preferably also well beyond the arm 10 of the supporting member, and being out of contact with the supporting member except for the one marked 20^a. They are secured to the insulation 13 by external threads of relatively large pitch on the contact members, and in practice the disc 13 is cored or bored with suitable holes for the members 20 and these members are then simply forced in with a twisting movement and are thus tightly held.

The outer ends of the contact members 20 are recessed at 21 to accommodate the projecting plug elements to be understood as forming a part of plug member 12 and fully illustrated

in my said copending application. The inner ends of the several contact or socket members 20 are bored at 22 and filled with solder so that when the user comes to apply wires thereto it is only necessary for him to hold the wire adjacent to the solder, apply a soldering iron until the solder softens, push the end of the wire into the recess 22 and let the solder harden. A neat and strong connection can thus be made with comparative ease in a construction where numerous wires come fairly close together.

In applying the device for use the cabinet should be provided with a hole as 23 large enough to accommodate the end of the casing of the plug member 12, and at such a place that when the supporting member 10—11 is secured in place the disc 13 will be coaxial with the hole 23. The socket member is thus protectively within the cabinet yet readily accessible from the outside.

It will be noted that the contact member 20^a passes through the arm 10 of the supporting member and is not insulated from that member. Since, however, there is no electrical connection between the metallic supporting member 10 and any of the other contact members 20, this electrical contact by the socket member 20^a is immaterial. In practice the element 20^a is used as the ground connection for the antenna. The arrangement shown not only permits the use of a considerable number of such contact elements in a substantially small space and in compact arrangement, but this connection between element 20^a and the support stabilizes and strengthens the relation of the disc 13 to the supporting member.

In Fig. 3 I have shown lines 25, 26, 27, 28, 40 29, 30 and 31 indicating wires connected to the terminals 20 and 20^a. Such wires are to be understood as leading to appropriate terminals of the set.

The device as thus constructed is peculiarly simple and strong and is particularly advantageous in the notable latitude it allows the user for making the desired connections at the most convenient place and to the best advantage with respect to the large amount 50 of other wiring and delicate instruments within the cabinet of a radio receiving set. Such a connection could be used in other electrical work also.

The construction is subject to some modification within the spirit of the invention, as indicated by the appended claims.

I claim:

1. A multiple socket device of the character described comprising in combination a metallic supporting member having a normally upright arm and a base part adapted to be secured in a relatively fixed position, a cylindrical mounting of insulating material, means for securing said mounting to said supporting member, said means comprising a

tubular member extending centrally through the mounting and through the arm of the supporting member, with a nut threaded on the end of said tubular member, and a plurality of long and narrow socket members carried by the mounting in spaced-apart relation to each other and extending substantially parallel with each other and beyond the rear surface of the mounting and being out of contact with the supporting member, said socket members having means at their inner ends for soldering wires thereto respectively and being recessed at their front ends for electrical connection with a multiple plug device.

2. A multiple connection device of the character described comprising in combination a supporting member having an upstanding arm and a base part adapted to be secured in a relatively fixed position, a cylindrical base of insulating material, means for securing said base to said supporting member, and a plurality of long and narrow contact members carried by the base in spaced-apart relation to each other and extending substantially parallel with each other and beyond the rear surface of the base, all of said contact members but one being free from the supporting member, said one thereof passing through the supporting member arm, said contact members being adapted at their inner ends respective for soldering wires thereto and having provisions at their outer ends for electrical connection with a coaxing multiple connection device.

3. An electrical connection socket member comprising in combination an insulation base of a form to fit telescopically into a coaxing plug member, a plurality of rod-like conductors rigidly held by the base and extending beyond the base on the inner side thereof sufficiently to extend through and beyond accommodating holes in a support when the inner side of the base rests upon one face surface of such support, said conductors being substantially parallel to each other and having respectively a hole therein extending longitudinally thereof and being open to the outer surface of said base and being adapted to receive a conductor plug element for electrical contact, and means for holding said base upon such support.

4. The combination of claim 3 hereof in which said base-holding means comprise a threaded bolt-like member carried by the base and adapted to extend through an accommodating hole in such support, and a nut member on said bolt-like member.

5. The combination of claim 3 hereof in which said base-holding means comprise a holding member carried by the base and having a longitudinal opening therein extending from the outer surface of said base and adapted to receive a guiding stem on a conductor plug member, with means for maintaining such guiding stem against admission into

said opening with the stem in all but one relative position.

6. The combination of claim 3 hereof in which said base is of cylindrical form and
5 said rod-like conductors are circularly arranged on said base and said base holding means are centrally arranged with respect to said conductors.

HOWARD B. JONES.
